UNITED STATES PATENT OFFICE.

LINFORD S. STILES, OF BROOKLYN, NEW YORK, ASSIGNOR OF ONE-FOURTH TO JOHN J. KUHN, OF NEW YORK, N. Y.

CINEMATOGRAPH.

1,308,875.

Specification of Letters Patent. Patented July 8, 1919.

Application filed March 4, 1915. Serial No. 12,014.

To all whom it may concern:

Be it known that I, LINFORD S. STILES, a citizen of the United States, and resident of Brooklyn, county of Kings, and State of New York, have invented an Improvement in Cinematographs, of which the following is a specification.

The object of my invention is to provide a moving picture machine of the cinematograph type which may be adapted for educational purposes, and more particularly for teaching dancing or other qualification in which certain movements or steps are required; for example, aside from the special dancing steps, the pictures may give exercising movements such as dumb-bell, fencing, and other exercises well known to those interested in athletics whether for sport or whether for health purposes, such as flesh reducing exercises, etc.

While the above are the primary objects of the invention, my improvements are also adapted for coöperation with a talking machine by providing a flexible detachable power transmitting connection from a rotating part of the talking machine, whereby the motor thereof may be employed to operate the cinematograph; and in this connection it is evident that the cinematograph may be employed to illustrate a dance while the Victrola is operated to play the dance music. To permit the timing of the dance to the music, I provide means on the cinematograph under the control of the operator to change the speed of the picture film to suit the speed of the music. It will furthermore be understood that my object is to enable the person operating the cinematograph to not only permit the machine to run in a continuous manner to give the appearance of motion, but the film may be stopped at any time so that any particular position illustrated in the picture may be carefully studied. In this manner, the operator has the power to see the individual positions as if they were ordinary photographs, and also has the power to see the positions in such rapid succession that the actual motions of the natural exercises would be apparent.

With these and other objects in view, my invention consists of certain novel features of construction of the cinematograph and its adaptability for connection with a talking machine, all of which are fully set out hereinafter and more particularly defined in the claims.

My invention will be better understood by reference to the drawings, in which:

Figure 1 is a rear elevation of my cinematograph apparatus; Fig. 2 is a sectional plan view of the same; and Fig. 3 is an elevation of part of the driving mechanism.

2 is the case and is adapted to stand upon a table or any other convenient support. This case may have a hinged back 3 which may be opened for purposes of providing access to the interior and especially for replacing the endless film. A snap catch or other fastener 5 may be employed for holding the back in closed position. Arranged within the case are the two drums 6 and 7, the latter being supported on a fixed axis, while the former is provided with a shaft 8 journaled in an adjustable bearing 9 adapted to slide in a suitable guideway 10 and spring pressed by a spring 11 so as to move the drum 6 away from the drum 7 for maintaining the endless film 38 under tension during operation, and to permit the drums to be moved relatively toward each other when it is desired to replace the film by another film. These drums may be provided with sprocket teeth and the films with sprocket holes, as is common in cinematograph and moving picture machines. I do not restrict myself in this regard. The sprocket drum 7 which is the driving drum is provided with a shaft 12 journaled in a bearing 13 and having its lower end slidably connected with the hub of a friction wheel 17, whereby it may be rotated by said friction wheel and at the same time said friction wheel may be adjusted longitudinally of the shaft. The rotating connection may be by a spline or any other suitable well known device which will positively rotate the shaft by the rotation of the friction wheel. The friction wheel 17 is journaled in a bracket 14 in which the shaft is also jour-

naled, as will be clearly understood by reference to Fig. 2, and this bracket 14 is guided vertically in the case 2 at 15. A spring 18 surrounds the shaft 12 and presses at one end upon the fixed bearing 13, and at the other end upon the adjustable bracket 14, so as to normally press said bracket away from the fixed bearing 13.

- 21 is a suitable motor which is shown by way of example as a spring motor having the winding arbor 23 by which the spring may be wound by the application of a key 24. This motor 21 is provided with a driving friction wheel 22, said wheel being driven by the pawl and ratchet device 39, the latter being secured to the arbor of the motor to permit winding thereof. A motor for this purpose would be of that type which is provided with a proper escapement device, such as a governor, to control its speed. Such motors are very common in talking machines and music boxes, and I therefore do not limit myself to any particular construction of the motor. The driving friction wheel 22 of the motor is in position to engage the perimeter of the friction wheel 17 when the latter is pushed axially by the push pin 20, slidably carried in the case in alinement with the hub of the friction wheel 17. When the friction wheel 17 is pushed in contact with the driving friction wheel 22, the spring 18 is compressed and the bracket 14 is moved upward. As long as the push-pin 20 is held in, the sprocket wheel 7 will cause the film 38 to be made to travel under the eye-piece 40 which may be provided with the usual lenses, and by which the pictures on the film may be viewed. The usual lamp and reflector 40^a may be arranged below the film. A shutter 25 may be employed as part of the whole mechanism to intermittently expose the pictures successively when they are squarely under the eye-piece, so that the impressions of the pictures come in rapid succession upon the eye for less than the whole period of movement of a picture under said eye-piece. The shutter may be driven by any suitable mechanical device such as a sprocket chain 26, so as to be in timed relation with the revolutions of the drum 7 which propels the film to make an intermittent exposure so as to expose each film a short period of time. The general arrangement of the eye-piece, the shutter and the film may be as in cinematographs heretofore well known, and I therefore do not restrict myself in any manner to the particular details thereof.
- It will be observed that by mere adjustment of the push-pin 20, the rotation of the driven friction wheel 17 may be interrupted so that the film may be brought to rest under the eye-piece 40 at any time desired. This will enable the person using the apparatus

to study the positions of objects, such as 65 dancers on the film. He has therefore the power of starting and stopping the film at will. If the film is to be run continuously, the adjusting screw 16 will be screwed up against the bracket 14 until the friction 70 wheel 17 is maintained in contact with the friction wheel 22. It will also be understood that the film may be driven at different speeds by simply adjusting the screw 16 to allow a slight separation between the friction wheels 17 and 22, and then by a sensitive pressure upon the push-pin 20 varying the frictional contact between the said friction wheels. By this hand adjustment, the operator may move the film at full speed 80 or at a slower speed or intermittently stop it, and thereby be able to study the motions and positions of the objects by which they are accomplished. In this way, a person may study a new dance and analyze it thoroughly. The same results may be accomplished with any form of exercise depicted upon the film, so that the device becomes an educational one. The films are preferably formed of an endless band of transparent 90 material such as celluloid and commonly employed in cinematograph and moving picture machines. By having the two drums 6 and 7 adjusted relatively to and from each other, it is manifest that by opening the 95 hinged back 3, the endless film 38 may be readily removed and a new film inserted and instantly put under tension by the action of the spring 11. While I prefer to employ endless films for the obvious reason that they 100 are easily applied and removed, it will be understood, however, that for some special uses where a greater number of exposures of the pictures are required, the film may be arranged in any other suitable manner. 105

In connection with the apparatus herein described, driving mechanism may be provided to rotate the film from a rotating part of an ordinary talking machine, and this is illustrated in Fig. 2 by mechanism comprising the following construction:—

Journaled in the case 2 is a shaft 27 having upon the inner end a small friction wheel 28 against which the driven friction wheel 17 may be pressed by the spring 18 when 115 permitted to do so by the adjustment of the screw 16. The contact position is shown in Fig. 2. Clamped to the end of the shaft 27 where it extends through the casing, is a coupling 30 which connects with one end of a flexible shaft 29. The other end of this flexible shaft is secured to a bevel pinion 31 which meshes with a bevel gear 32 having a rubber bushing 34 that may be crowded over a rotatable part of the talking machine. As shown, it is crowded over the hub 35 of the turn-table which carries the record. The end of the flexible shaft adja- 120 125

cent to the pinion 31 is journaled in a bearing 33 which is sleeved upon the hub of the gear 32, so that both of the gears may rotate relatively to the bearing 33 and yet the latter holds them in proper relation. In this manner, the cinematograph machine may be readily connected with a talking machine and driven by its motor, and at the same time, the cinematograph will have all the provisions for control which have heretofore been described. When connected with a talking machine, suitable music may be provided while the cinematograph is operating, as will be well understood. In the operation with the talking machine, should the dancing pictures lag, they may be speeded up by pressing the button 20 to bring the friction wheel 17 into contact with the wheel 22 of motor 21, and after the film is advanced to catch up to the music, the button 20 may be released and the mechanism driven from the talking machine as before. While a talking machine is an available source of power, irrespective of the accompanying music, the flexible shaft and the terminal gears may be adapted for connection with any other suitable motor device that is available, and the flexible shaft permits the positioning of the cinematograph device for convenience in watching the film.

I have shown my invention in one form as to its details, but it is to be kept in mind that the power transmitting devices between the motive power and the film may be varied greatly, and I therefore do not restrict myself to the details as these may be modified in various ways without departing from the spirit of the invention.

Having now described my invention, what I claim as new and desire to secure by Letters Patent, is:

1. In an apparatus of the character stated, a case, a pair of rolls arranged in the case, a film of pictures arranged about the rolls, means to put the film under tension, means on the case for viewing the pictures of the film as they travel under it, a power motor arranged within the case, power transmitting connections between the power motor and one of the rolls, spring actuated means for normally keeping the power transmitting devices out of operation, and hand controlled means for opposing the action of the spring and putting said power transmitting devices into operation whereby the power motor may rotate the roll which drives the film.

2. In an apparatus of the character stated, a case, a pair of rolls arranged in the case, a film of pictures arranged about the rolls, means to put the film under tension, means on the case for viewing the pictures of the film as they travel under it, a power motor arranged within the case, power transmitting

connections between the power motor and one of the rolls, spring actuated means for normally keeping the power transmitting devices out of operation, and hand controlled friction means for opposing the action of the spring, and putting said power transmitting devices into operation whereby the power motor may rotate the roll which drives the film and the speed of the said roll varied or stopped at the will of the operator.

3. In an apparatus of the character stated, a case, a pair of rolls arranged in the case, a film of pictures arranged about the rolls, means to put the film under tension, means on the case for viewing the pictures of the film as they travel under it, a power motor arranged within the case, power transmitting connections between the power motor and one of the rolls, means for normally keeping the power transmitting devices out of operation, hand controlled means for putting said power transmitting devices into operation whereby the power motor may rotate the roll which drives the film, and separate manually operated means for maintaining the power transmitting connections in operation.

4. In an apparatus of the character stated, a case, a pair of rolls arranged in the case, a film of pictures arranged about the rolls, means to put the film under tension, means on the case for viewing the pictures of the film as they travel under it, a power motor arranged within the case, a rotatable shaft also journaled in the case, power transmitting connections for operating one of the rolls to move the film, hand controlled means for putting the power transmitting connections into operation from the power motor or from the separate rotatable shaft, a rotatable member arranged to be driven from a moving part of a talking machine, and a flexible shaft extending from the rotatable member for driving the rotatable shaft of the casing whereby the film may be driven from either of the sources of power at the will of the operator.

5. In an apparatus of the character stated, a case, a pair of rolls arranged in the case, a film of pictures arranged about the rolls, means to put the film under tension, means on the case for viewing the pictures of the film as they travel under it, a spring motor arranged within the case, a rotatable shaft also journaled in the case, power transmitting connections for operating one of the rolls to move the film, hand controlled means for putting the power transmitting connections into operation from the spring motor or from the separate rotatable shaft, a rotatable member arranged to be driven from a moving part of a talking machine, a detachable connection for a talking machine consisting of a pair of bevel gears engaging

each other and mechanically united into operative relation, a frictional socket for one of the gears arranged to fit the hub of a rotating part of the talking machine, and a flexible shaft connecting with the other of the gears and extending to the rotatable member for driving the rotatable shaft of the casing whereby the film may be driven

from either of the sources of power at the will of the operator. 10

In testimony of which invention, I hereunto set my hand.

LINFORD S. STILES.
